CLOCK

Joseph H. Dold, 5920 N. 11th St., Philadelphia, Pa.

Filed Aug. 13, 1962, Ser. No. 71,255

Term of patent 14 years

(Cl. D42—7)

FIG. 1 is a plan view of a clock showing my new design with the hour hand at noon and wherein contrasting shades are exposed through the arcuate cutouts in the face of the clock;

FIG. 2 is a side elevational view of the clock works with the casing removed for convenience of illustration;

FIG. 3 is a side elevational view partly in section of the clock shown in FIG. 1; and

FIG. 4 is a fragmentary plan view of the face of the clock with the hour hand at midnight.

The casing for the clock has been broken away in FIGS. 1 to 3, inclusive, for convenience of illustration.

The dominant features of the design reside in the portions shown in full lines and especially the single hour hand mounting the sun and moon thereon and the circumferentially staggered arcuate cutouts whereby the sun

is exposed through one of the cutouts during the daylight hours and the moon is exposed through the other cutout during the night hours.

I claim:

The ornamental design for a clock, as shown and described.
